GUN LOCK FOR TRIGGER GUARD

Edward R. Buchanan, Seattle, Wash.

Application October 17, 1956, Serial No. 616,412

4 Claims. (Cl. 42—1)

2

kerfed heads 20. The projecting end portions of the set-screws 17 are insertable in the cup 9 through openings 21 provided therefor in the side wall 13 of said cup.

Rotatably mounted in the cup 9 on the side wall 13 thereof between the openings 21 is a disk 22. A pair of bolts 23 have one end portion pivotally connected off-center to the disk 22, as indicated at 24. The free end portions of the bolts 23 are slideable in guides 25 which are provided therefor in the cup 9. The disk 22 is actuated by a suitable lock 26 on the cup 9. The bolts 23 are engageable with the necks 19 behind the heads 20 of the screws 17. Toward this end, the bolts 23 are provided in their free ends with notches or recesses 27 for the reception of the screws 17.

It is thought that the use of the device will be readily apparent from a consideration of the foregoing. Briefly, the cup 9 is slipped upwardly over the trigger guard 7 beneath the gun 6. The straps 10 are then engaged over the gun 6, the plates 15 are adjusted, if necessary, on said straps and secured by the screws 17 and said screws are then inserted in the cup 9 through the openings 21. Through the medium of a suitable key the lock 26 is then actuated for projecting the bolts 23 into engagement with the screws 17 for securing the connectors 14 in position on the cup 9. It will thus be seen that the trigger 8 is completely enclosed and shielded for preventing unauthorized use of the gun or the accidental firing thereof. Of course, to remove the device the foregoing procedure is substantially reversed. If desired, the bolts 23 may be spring projected.

The foregoing is considered as illustrative only of the principles of the invention. Further, since numerous modifications and changes will readily occur to those skilled in the art, it is not desired to limit the invention to the exact construction and operation shown and described, and accordingly, all suitable modifications and equivalents may be resorted to, falling within the scope of the invention as claimed.

What is claimed as new is as follows:

40 1. A gun lock of the character described comprising: a cup engageable beneath the gun and adapted to receive the trigger and the trigger guard thereof, a pair of substantially U-shaped attaching straps straddling the gun and having one end portion anchored to one side of the cup, and means adjustably and detachably connecting the other end portions of said straps to the other side of said cup, said means including plates having slots therein slidably receiving the straps, screws threadedly mounted in the plates and engaged with the straps for securing said plates in adjusted position thereof, and means securing said screws on the cup.

45 2. A gun lock of the character described comprising: a cup engageable beneath the gun and adapted to receive the trigger and trigger guard thereof, substantially U-shaped attaching straps straddling the gun and having one end portion pivotally secured to the cup, said cup having a pair of openings therein, a pair of plates mounted for sliding adjustment on the other end portions of the straps, screws threadedly mounted in the plates and engaged with the straps for securing said plates in adjusted position thereon, said screws being insertable in the cup through the openings, and means in the cup for anchoring the screws therein.

50 3. A gun lock of the character described comprising: a cup engageable beneath the gun and adapted to receive the trigger and trigger guard thereof, substantially U-shaped attaching straps straddling the gun and having one end portion pivotally secured to the cup, said cup having a pair of openings therein, a pair of plates mounted for sliding adjustment on the other end portions of the straps, screws threadedly mounted in the plates and engaged with the straps for securing said plates in adjusted

The present invention relates to new and useful improvements in locks for firearms and has for its primary object to provide, in a manner as hereinafter set forth, novel key controlled means for enclosing the trigger and its guard for preventing unauthorized use of the gun and unintentional or accidental operation of said trigger.

Another very important object of the invention is to provide a firearm lock or guard of the character described comprising novel adjustable attaching means whereby the device may be readily mounted for use on various conventional guns without altering same structurally in any way.

Other objects of the invention are to provide a gun lock or guard of the aforementioned character which will be comparatively simple in construction, strong, durable, compact, attractive in appearance and which may be manufactured at low cost.

These together with other objects and advantages which will become subsequently apparent reside in the details of construction and operation as more fully hereinafter described and claimed, reference being had to the accompanying drawing forming a part hereof, wherein like numerals refer to like parts throughout, and in which:

Figure 1 is a view in side elevation, showing an embodiment of the present invention mounted on a gun;

Figure 2 is a view in vertical longitudinal section through the device;

Figure 3 is a view in transverse section, taken substantially on the line 3—3 of Figure 2;

Figure 4 is a view in vertical section through the adjustable connecting means for one end portion of the attaching straps; and

Figure 5 is a detail view in side elevation of one of the lock bolts.

Referring now to the drawing in detail, it will be seen that reference character 6 designates an intermediate portion of a conventional gun provided with the usual guard 7 for the trigger 8. The embodiment of the present invention which has been illustrated comprises an elongated metallic cup 9 which is engageable beneath the gun 6 for enclosing the guard 7 and the trigger 8. As shown to advantage in Figure 3 of the drawing, the cup 9 is substantially U-shaped in transverse section.

A pair of substantially U-shaped resilient metallic straps 10 removably secure the cup 9 in position beneath the gun 6. The straps 10 straddle the gun 6 and have one end portion pivotally secured, as indicated at 11, to one of the side walls 12 of the cup 9.

The other end portions of the straps 10 are adjustably and detachably secured to the other side wall 13 of the cup 9 by metallic connectors 14. The connectors 14 comprise metallic blocks or plates 15 having slots 16 extending vertically therethrough for slidably receiving the straps 10. Set-screws 17 are threadedly mounted in the inner sides of the plates 15 and engaged with the straps 10 for securing said straps in adjusted position in said plates. Threaded openings 18 in the plates 15 accommodate the set-screws 17. The set-screws 17 comprise reduced necks 19 projecting from the plates 15 and terminating in

position thereon, said screws being insertable in the cup through the openings, and means in the cup for anchoring the screws therein, said means including a disk rotatably mounted in the cup, and a pair of bolts slidably mounted in the cup and having one end portion pivotally secured off-center to the disk for actuation thereby, the free ends of said bolts being engageable with the screws.

4. A gun lock of the character described comprising: an elongated metallic cup of substantially U-shaped transverse section engageable beneath the gun for receiving and enclosing the trigger and trigger-guard thereof, a pair of substantially U-shaped attaching straps of resilient metal straddling the gun and having one end portion pivotally secured to one side of the cup at longitudinally spaced points, the other side of said cup having longitudinally spaced openings therein, and means for adjustably and detachably securing the other end portions of the straps to the cup, part of said last mentioned means being engageable in the openings, said means including slotted plates mounted for sliding adjustment on the

10

straps, screws threadedly mounted in the plates and engaged with the straps for securing said plates in adjusted position thereon, said screws projecting from said plates and being insertable in the cup through the openings, said screws including heads on the inner ends thereof, and bolts in the cup engageable with the screws behind the heads thereof for anchoring said screws in the cup.
